UNITED STATES PATENT OFFICE.

GEORGE W. BOOTH, OF NEW TORONTO, ONTARIO, CANADA.

TUNNEL KILN.

Application filed February 19, 1925. Serial No. 10,415.

This invention relates to tunnel kilns, and more particularly to those employed in manufacturing clay products which require to be passed through three heat stages and one cooling stage. This is accomplished by forming the kiln with a drying chamber and preheating, firing and cooling zones. The general arrangement has been to build the three zones in alinement and separate them, by means of doors, and to build the drying chamber at one side of the main part of the kiln. In some instances the drying zone or chamber has been located in alinement with the other zones but with either of these arrangements there is considerable waste in heating the drying chamber and unnecessary land and construction material is used for building the drying chamber. My object is to provide a kiln in which the drying chamber is so located that it may be easily heated by otherwise waste heat and may be built at a saving in cost, both in labor and material and in land required.

I attain my object by means of the constructions hereinafter described and illustrated in the accompanying drawings in which—

Fig. 1 is a side elevation of my improved kiln;

Fig. 2 a cross section on the line 2—2 in Fig. 1;

Fig. 3 a cross section on the line 3—3 in Fig. 1;

Fig. 4 a cross section on the line 4—4; and

Fig. 5 a longitudinal section on the line 5—5 in Fig. 2.

In the drawings like numerals of reference indicate corresponding parts in the different figures.

1 is the tunnel kiln which as usual comprises drying, preheating, firing and cooling zones. The preheating zone extends from A to B, see Fig. 1, the firing zone from B to C, and the cooling zone from C to D. In the walls of the kiln at opposite sides of the firing zone are located the furnaces 2. The products of combustion from these furnaces are drawn through flues 3 formed at opposite sides of the preheating zone which is a common construction.

Heretofore the drying zone or chamber 4 has been located either in alinement with the other zones of the kiln or to one side thereof which necessitated the use of a long conduit or passage for conveying air, preheated by passing it over the firing and cool-

ing zones, to the drying chamber. The loss of heat in these passages is so great that in some instances the drying chamber has been provided with a separate heating plant for removing the moisture from the ware before it is passed through the firing zone. This air passage has to be built at the top of the kiln to obtain the most heat and therefore greatly increases the cost of constructing a kiln. To overcome the above objectionable features I arrange my drying chamber 4 on top of the kiln. With this arrangement it is only necessary to build the side walls of the kiln a few feet higher as the roof formerly used for the air passage will serve for the roof of the drying chamber. It is obvious that the drying chamber will not require any additional land and thus another saving is effected.

Preferably there are two drying chambers 4 formed on top of the tunnel kiln and extending from end to end of the latter. An air passage 5 is formed at each side of the kiln and these passages communicate, by means of damper controlled openings 5^a, with their adjacent chambers. Each of the said passages extends longitudinally of the kiln adjacent the cooling and firing zones and communicates with the atmosphere by means of damper controlled openings 5^b and 5^c respectively. The openings 5^c are located above the furnaces 2, and the openings 5^b communicate with air passages 5^d extending longitudinally of the cooling zone. These passages communicate, by means of a plurality of openings 5^e with the portions of the passages 5 adjacent the cooling zone. With this arrangement the air entering the openings 5^b serves to cool the ware in the cooling zone and the heated air rises into the passages 5 and thence into the chambers 4. Each chamber is provided with a moist air flue 6 extending longitudinally thereof and having a plurality of damper controlled openings 6^a communicating with the interior of the chamber. Each flue 6 is provided with a damper controlled opening 6^b which forms a communication between the flue 6 and a transverse flue 7^b which communicates with a stack 7.

This stack is also adapted to draw the products of combustion through the flues 3 and past the walls of the drying chambers in the following manner. Flues 3^a are formed at opposite sides of the kiln adjacent the drying chambers and these flues commu-

nicate by means of damper controlled openings 3^b with the flues 3. Each of the flues 3^a communicates, by means of a damper controlled opening, with the transverse flue 7^b.

5 Assuming the kiln is in full operation the modus operandi is as follows. The ware to be treated enters the left hand ends of the drying chambers (Fig. 1) over the preheating zone. As the ware progresses towards 10 the right the heat of the air passing through the passages 5 and into the chambers becomes more intense. This is due to the walls of the kiln being hotter near the furnaces. After passing through the portions of the 15 chambers located over the top of the cooling zone, the ware is lowered to the level of the preheating zone and passed through it, and then through the firing and cooling zones, coming out at the end of the kiln opposite 20 to the end of the drying chamber it entered. Any means such as a block and tackle, chute, or hoist 8 may be employed for lowering and raising the ware from the discharge and entering ends of the drying chambers.

25 The moisture is removed from the ware as it is passed through the drying chamber and before it is passed into the preheating zone.

30 Preferably the passages 5 and flues 3^a are separated by a wall or partition 9 to remove any possibility of the products of combustion passing into the passages. The air is drawn by means of the stack 7, into the passages 5, through the openings 5^a, chambers 35 4, openings 6^a, moist air flues 6, openings 6^b and transverse flue 7^a.

35 It will be understood that various modifications, such as using one drying chamber extended only part way of the total length 40 of the kiln and re-arranging the air passages may be used without departing from the spirit of my invention.

What I claim is:

1. The combination of a tunnel kiln; a 45 separate drying chamber arranged at the top of the kiln whereby the chamber will be heated by conduction from the kiln; an air passage formed longitudinally in a wall of the chamber and adjacent the kiln, the passage having a series of openings communicating with the interior of the chamber; a moist air flue extending longitudinally of the kiln communicating with the interior of the chamber; and means for drawing air through the said passage, chamber and flue.

2. The combination of a tunnel kiln; a 60 separate drying chamber arranged at the top of the kiln whereby the chamber will be heated by conduction from the kiln; a flue formed in a wall of the drying chamber and extending longitudinally thereof; a furnace; and means for drawing the products of combustion through the said flue from the kiln, while the furnace is in operation.

65 3. The combination of a tunnel kiln; a

separate drying chamber arranged at the top of the kiln whereby the chamber will be heated by conduction from the kiln; an air passage extending along the wall of a hot zone of the kiln for conveying air so that it 70 will be heated by the kiln and extending along a wall of the chamber for heating the latter; a flue formed in a wall of the drying chamber; and extending longitudinally thereof; a furnace; and means for drawing the products of combustion through the said flue from the kiln.

4. The combination of a tunnel kiln; a 75 separate drying chamber arranged at the top of the kiln whereby the chamber will be heated by conduction from the kiln; an air passage formed longitudinally in a side wall of the chamber and extending along the wall of a hot zone of the kiln, the passage having a plurality of spaced openings communicating with the interior of the chamber; and means for drawing air through the passage and chamber.

5. The combination of a tunnel kiln; a 80 separate drying chamber arranged at the top of the kiln whereby the chamber will be heated by conduction from the kiln; a furnace; a stack; and a longitudinal flue formed in the wall of the kiln and chamber and communicating with the furnace and stack 85 whereby the products of combustion will assist in heating the chamber.

6. The combination of a tunnel kiln; a 90 separate drying chamber arranged at the top of the kiln whereby the chamber will be heated by conduction from the kiln; an air passage formed longitudinally in a side wall of the chamber and extending along a hot zone of the kiln, the passage having a 95 plurality of spaced openings communicating with the interior of the chamber; a moist air flue communicating with the interior of the chamber at different points in its length; and means for drawing air through the passage, chamber and flue.

7. The combination of a tunnel kiln; a 100 separate drying chamber arranged at the top of the kiln whereby the chamber will be heated by conduction from the kiln; an air passage formed longitudinally in a side 105 wall of the chamber, the passage having a plurality of spaced openings communicating with the interior of the chamber; a moist air flue communicating with the interior of the chamber; a flue formed in a wall of the 110 chamber and separated from the said passage and moist air flue; and means for drawing air through the passage, chamber, and moist air flue, and also for drawing the products of combustion through the 115 second mentioned flue.

8. A tunnel kiln provided with firing and cooling zones; a separate drying chamber arranged at the top of the kiln and over the said zones; a longitudinal air passage 120

in the kiln adjacent the said zones and chamber, the passage having a plurality of spaced openings communicating with the interior of the chamber; a moist air flue 5 communicating with the interior of the chamber; and means for causing a circulation of air through the said passage, openings and flue.

9. The combination of a tunnel kiln; a separate drying chamber arranged at the top of the kiln whereby the chamber will be heated by conduction from the kiln; a passageway arranged longitudinally of the chamber and within the kiln adjacent the 15 said zones and provided with a controlled opening for admitting air thereto, the passage also having a plurality of controlled openings communicating with the interior of the chamber; and means for causing a 20 circulation of air through the passage and chamber.

10. A tunnel kiln provided with preheating, firing and cooling zones; a separate drying chamber arranged at the top of the 25 kiln and over the said zones; an air passage extending longitudinally of the firing and cooling zones and communicating with the interior of the chamber; and a flue extending longitudinally of the preheating zone 30 and adjacent the chamber for carrying the products of combustion past the latter.

11. A tunnel kiln provided with preheating, firing and cooling zones; a separate drying chamber arranged at the top of the 35 kiln and over the said zones; an air passage extending longitudinally of the firing and cooling zones at one side of the kiln and provided with a plurality of openings communicating with the interior of the chamber; and a moist air flue located at the side 40 of the chamber opposite the air passage, the said flue having a plurality of openings communicating with the interior of the chamber; and a flue extending longitudinally of the preheating zone and adjacent 45

the chamber for carrying the products of combustion past the latter.

12. A tunnel kiln provided with preheating, firing and cooling zones; two separate drying chambers arranged side by side at 50 the top of the kiln and over the said zones and separate therefrom; air passages extending longitudinally of the firing and cooling zones at opposite sides of the kiln, each passage being provided with openings 55 communicating with the interior of the adjacent chamber; a moist air flue for each chamber arranged longitudinally thereof at the side opposite the air passage and provided with a plurality of openings communicating with its chamber; flues extending longitudinally of the preheating zone at opposite sides of the kiln and adjacent the chamber; and means for drawing the products of combustion through the last men- 60 tioned flue and for causing a circulation of air through the said passages, chambers and moist air flues.

13. The combination of a tunnel kiln; a separate drying chamber arranged at the 70 top of the kiln; means for preheating air and controlling its inlet into one end only of the chamber; and means for conveying the products of combustion through the wall adjacent the other end only of the chamber. 75

14. The combination of a tunnel kiln; a separate drying chamber arranged at the top of the kiln; suction means; means communicating with the suction means for 80 causing a circulation of air through one end of the chamber; and means communicating with the suction means for conveying the products of combustion through the wall adjacent the other end only of the 85 chamber.

Signed at Toronto, Canada, this 13th day of Feb., 1925.

GEORGE W. BOOTH.
